SWIMMING POOL FLOATING DISPENSER

Amello F. Fedrigo, 35750 Industrial Road,
Livonia, Mich. 48150

Filed Jan. 7, 1972, Ser. No. 216,330

Term of patent 14 years

Int. Cl. D23—01

U.S. Cl. D23—3

FIG. 1 is a perspective view of a swimming pool floating dispenser showing my new design;

FIG. 2 is a top plan view thereof;

FIG. 3 is a side elevational view thereof; and

FIG. 4 is a bottom plan view thereof.

I claim:

The ornamental design for a swimming pool floating dispenser, as shown.
